UNITED STATES PATENT OFFICE.

ARTHUR S. BURNELL, OF MARSHALLTOWN, IOWA.

FLEXIBLE FLAT-METAL FLOOR-MAT.

SPECIFICATION forming part of Letters Patent No. 737,574, dated September 1, 1903.

Application filed January 28, 1902. Serial No. 91,646. (No model.)

To all whom it may concern:

Be it known that I, ARTHUR S. BURNELL, residing in the city of Marshalltown, in the county of Marshall and State of Iowa, have invented certain new and useful Improvements in Mats, of which the following is a full, clear, and exact description.

The invention relates more particularly to mats formed of strips of metal flexibly connected together.

It has heretofore been common to construct metal mats of transverse sections pivotally connected together by transverse pivot rods or bars, which render the mat flexible longitudinally. In practice it has been found that the marginal portions have a tendency to bend upwardly or become warped as a result of the continuous lateral impact from the heels of boots or shoes. Furthermore, in cleaning such mats the mat is frequently grasped at one edge or corner thereof, and as a result the mat becomes warped or out of transverse alinement, and thus causes portions of the mat to be raised above the floor when the mat is in use and so the portions of the mat will receive the impact of boots and shoes, which renders the mat quite uneven and unsatisfactory in use.

The present invention designs to overcome these objections to mats as heretofore constructed and to provide a mat which is flexible along a longitudinal line or lines, so that if the marginal portion of the mat is lifted upwardly it will readjust itself to the floor and render the marginal portions sufficiently yielding to cushion the impact thereagainst of boots or shoes.

The invention also designs to provide an improved clip formed of flat metal in which the abutting faces of adjacent strips are rigidly secured to each other.

Another object of the invention is to improve the construction of mats composed of a series of short flat metal strips having portions between their ends bent laterally. In the use of such strips it has been found that lateral impact tends to flatten or expand the strips in longitudinal direction. To render such strips inexpandible, it has been proposed to employ straight marginal links forming a border for the mat. When, however, the straight links are used to form the side strips

or margins, they frequently become bent and cause the transverse pivot-rods to also become bent.

With this object in view the invention provides a construction in which the inexpandible strips are protected from lateral impact and are so arranged that there is little or no danger of becoming bent.

The invention further designs to provide an improved end strip for mats.

The invention consists in the several novel features of construction hereinafter described, illustrated in the accompanying drawings, and more particularly defined by claims at the conclusion hereof.

In the drawings, Figure 1 is a plan view of a portion of an end strip. Fig. 2 is a section of an end portion of a mat. Fig. 3 is a perspective view of a portion of a mat. Fig. 4 is a detail perspective view showing the clips which yieldingly connect the parts of a section. Fig. 5 is a plan view of a mat embodying the preferred form of the invention.

The mat is formed of a plurality of transverse sections, each of which comprises a plurality of short strips of flat metal *b*, having straight alined terminals *b'* and a central portion bent laterally, as at *b*². The strips are alternately arranged to form meshes and so the laterally-bent central portions *b*² will be contiguous and abut against each other.

Through the overlapping terminals *b'* of the strips of adjacent sections extend transverse pivot-rods *c*, whereby the sections are connected together to permit the sections of the mat to be rolled or folded around each other and so the mat will be substantially inflexible transversely. The ends of rod *c* are provided with suitable heads *c'*, whereby the strips are transversely positioned on the rods.

Rods *c* are formed of wire, and heads *c'* are preferably formed by looping the rod-terminal. The marginal strips *b*³ form a side border, and their central portions project laterally a sufficient extent to protect the heads *c'* of the pivot-rods from breakage. Adjacent the marginal strips of each section a straight link *d* is arranged, and the pivot-rods *c* extend through the overlapping terminals of longitudinally-adjacent links. Strips having portions intermediate the terminals bent laterally tend to expand slightly when sub-

jected to lateral strains or pressure. To overcome the possibility of stretching or straightening the marginal strips b^3 , the straight links d are arranged in close proximity and inside of the border to protect the straight links from the strains and impact to which the border is subjected and which tends to bend the links and draw the pivot-rods toward each other. These straight links when located adjacent the border are protected from the severe strain to which the border is subjected and secure the marginal strips b^3 against all danger of becoming flattened or bent and secure the rods against displacement. Straight links d may also be located in the body of the mat at desired intervals.

To render the mat flexible along a longitudinal line or lines, each transverse section is formed of a plurality of portions connected together by a clip e , comprising two strips of metal, each of which has straight aligned terminals and a portion between the terminals bent laterally and there formed with a straight surface e' , abutting against the corresponding surface of the other strip and secured together by a rivet f , which secures the strips together. The strips of each clip e are respectively connected with the transverse pivot-rods of each portion of a transverse section. The pivot-rods extend through the perforated terminals of each strip of clip e and are secured on said rods by heads c' , formed on said rods and adjacent to the inner faces and between the terminals of the strips of a clip e . The clips are formed of strips of thin metal, which have only a slight and loose bearing on the cross-rods, and therefore the clips connect the parts of a section and permit limited vertical flexure of one portion of a section with respect to another. Pivot-rods c extend through only the overlapped terminals of adjacent portions of the sections and connect contiguous portions of adjoining transverse sections—that is, independent rods extend through the several portions to permit flexure of the mat on a longitudinal line or lines between the several portions of the transverse sections. The portions of each transverse section are connected together by a series of clips e , longitudinally aligned. These clips have independent connections with transversely-adjacent portions of a section and have their central portions riveted together and provide a joint between the portions of the transverse sections which permits limited flexure of the mat on a longitudinal line or lines and which does not interfere with the rolling or folding of the mat. As a result of this construction the mat is flexible on a longitudinal line, so that the marginal portions of the mat when subjected to severe strain can yield along a longitudinal line instead of straining or bending the strips and rods. Furthermore, the marginal portion being somewhat flexible on a longitudinal line will readily adjust itself to a floor, and thus provide a uniform sup-

port for the several strips, so the mat will present a substantially even surface and will not become bent or warped on account of the strains resulting from impact against the mat by reason of its unevenness.

End pieces a are formed of a straight piece of malleable metal having a groove a' in its inner edge and extending from end to end thereof and having intersecting transverse slots a^2 , which retain and form seats for the terminals of the strips of an end section of a mat. Groove a is adapted to hold a transverse rod c^4 , which extends longitudinally therethrough and through the strip-terminals of the end section. Rods c^4 are secured in groove a' by pressing together the upper and lower edge portions adjacent the groove, as shown in Fig. 3, and advantageously connect the rigid end strips with the end section of the mat. The end pieces a are formed of strips corresponding in length to the portions of the transverse sections to permit flexure of the mat along the line of clips e and which may be provided at desired intervals, according to the width of the mat.

The invention is not to be understood as restricted to the precise form shown and described, but may be varied without departing from the spirit of the invention.

Having thus described my invention, what I claim as new, and desire to secure by Letters Patent, is—

1. In a metal mat, the combination with a series of sections flexibly connected, of an end strip formed of a strip of metal having a groove in its inner edge and extending from end to end and transverse slots intersecting said groove, and means connecting the strip and one of the sections.

2. In a metal mat, the combination with an end strip formed of metal and having a longitudinal groove in its inner edge extending from end to end and a plurality of transverse slots intersecting the longitudinal groove, of a plurality of flat strips of metal having their terminals perforated and having their outer perforated ends inserted in the transverse slots of the end strip and a wire extended through the longitudinal groove and the terminals of the strips in the slots, the longitudinal slot being contracted at its inner edge to retain the rod.

3. A mat consisting of a plurality of transverse sections flexibly connected, the sections being formed of rigid portions and a yielding connection between the portions of a section, whereby the mat will be rendered limitedly flexible along a longitudinal line.

4. A mat consisting of a plurality of sections, said sections consisting of rigid portions, transverse pivot-rods flexibly connecting the sections, the rigid portions of the sections being formed of flat strip metal, and a yielding connection between the portions of a section whereby the mat will be rendered limitedly flexible along a longitudinal line.

5. A mat consisting of a plurality of sec-

tions, said sections consisting of rigid portions, the rigid portions of the sections being formed of flat strip metal and separate transverse pivot-rods connecting each portion of a 5 section with the corresponding portion of the next section, and a connection between the portions of a section, whereby the mat will be rendered limitedly flexible along a longitudinal line.

o 6. A mat consisting of a plurality of sections formed of flat strip metal, said sections being formed of a plurality of rigid portions, separate transverse pivot-rods extending through the strips of adjacent sections and a 15 clip forming a connection between the portions of a section and connected with the pivot-rods of the portions of a section.

7. A mat consisting of a plurality of sections formed of flat strip metal, said sections 20 being formed of a plurality of rigid portions, separate transverse pivot-rods extending through the strips of adjacent sections and a connection between the portions of a section, and comprising strips respectively connected 25 with the portions of a section, and secured to each other.

8. In a mat formed of sections the combination of a plurality of flat metal strips and transverse pivots connecting the strips, said

strips extending longitudinally between said 30 pivots and being bent laterally between their ends, and rigidly secured to one of the transversely-adjacent strips.

9. In a mat formed of sections the combination of a plurality of flat metal strips and 35 transverse pivots connecting the strips, said strips extending longitudinally between said pivots and being bent laterally between their ends and rivets extended through the laterally-bent portions of transversely-adjacent 40 strips.

10. A mat comprising a plurality of strips of flat metal having their ends perforated and connected with longitudinally-adjacent strips, by transverse pivot-rods, and having 45 their straight terminals perforated and having portions between the straight terminals bent laterally, a side border formed of said strips and straight links adjacent said border and having perforations in their terminals through which the rods extend, said links being within the side border of the mat and between said strips.
